UNITED STATES PATENT OFFICE.

ISAAC WATTS FURMAN, OF BAY SHORE, NEW YORK.

AUTOMOBILE-JACK.

1,140,149.

Specification of Letters Patent. Patented May 18, 1915.

Application filed November 18, 1914. Serial No. 872,735.

To all whom it may concern:

Be it known that I, ISAAC W. FURMAN, a citizen of the United States, and a resident of Bay Shore, in the county of Suffolk and State of New York, have invented a new and Improved Automobile-Jack, of which the following is a full, clear, and exact description.

Among the principal objects which the present invention has in view are: to provide means for lifting a vehicle of the character indicated in one operation; to provide means for rotating the vehicle about a self-contained center; and to provide a rotary supporting apparatus adapted for removal from its service position.

Drawings: Figure 1 is a side view of a jack constructed and arranged in accordance with the present invention and showing in conjunction therewith an automobile, the same being supported in lifted position thereon. Fig. 2 is a top plan view of a jack constructed and arranged in accordance with the present invention, one of the bosses being sectioned to show the method of mounting the supporting arms therein; Fig. 3 is a detail view on an enlarged scale and in section, the section being taken as on the line 3—3 in Fig. 2; Fig. 4 is a horizontal section taken on the line 4—4 in Fig. 3.

As seen in the accompanying drawings, a jack screw 9 is provided with a suitable screw-thread to engage a tapped perforation in the boss 10 of a base plate 11. The base plate 11 is preferably anchored on a cement foundation 12, as best seen in Fig. 3 of the drawings. Anchor bolts 13 are employed to hold the base plate 11 in service position.

The jack screw 9 is provided with a head 14, through which extend perforations 15 provided to receive and hold the end of a winch bar 16 employed to rotate the screw 9 to elevate or lower a table 17.

The table 17 is centrally bored to receive the reduced pivot end 18 of the screw 9. The table 17 is directly supported by an annular shoulder formed on the head 14 at the junction of said head with the pivot end 18. Said table is not anchored on the screw 9, it being desired that a certain amount of movement on the part of the table should be permitted. Adjacent the outer edge of the table 17 a circular groove is provided to form a race for balls 19.

After the balls 19 are disposed in the race provided therefor, as seen best in Fig. 4 of

the drawings, a spider body 20 is placed thereon, a central perforation being provided in said body, through which passes the pivot end 18. The body 20 is made sufficiently heavy and strong and has radiated therefrom in substantially opposite and diverged directions, socket bosses 21. Usually there are four bosses, as seen best in Fig. 2 of the drawings. These bosses are axially bored to loosely receive spider arms 22. The bosses 21 and the bores formed therein are sufficiently long to permit an adjustment of the arms 22 lengthwise of the sockets or bores thereof. The adjustment thus provided for permits sufficient expansion and contraction of the spider arms 22 to adapt the jack for use on various sizes of automobile vehicles.

At the extreme ends of each arm 22 is formed a saddle or crook 26, in which is seated the axle or other suitable part of an automobile or other vehicle. To reinforce or strengthen the arms 22, they may be provided with a truss bar 23 having a strut 24, or an equivalent construction, such as a continuous and integral web extending from the under side of each of said arms. It will also be understood that for light vehicles the truss and equivalent devices may be dispensed with.

The body 20 is held in service by a nut 25. The nut 25 or other fastening device for holding the body 20 in position is used only where the jack is retained permanently in position to be employed as in large garages where the jack is generally located on what is known as the washing floor, being employed as an accessory to the operation of washing.

Usually, however, the body 20 and arms 22 are removed from the screw 9, as is also the winch bar 16. If the arms 22 are retained in the socket posts of the bosses 21, the spider structure is disposed of in any suitable manner. Where desired, however, the arms 22 may be removed from the sockets and disposed of independently or with the body 20 and winch bar 16. In cases where it is desired, it is obvious that the screw 9 may be removed from the base plate 11, when the floor of the garage will be practically unobstructed.

The present jack is employed principally as an adjunct to a washing or painting station, and the foundation 12 is usually the draining floor of said station. When em-

ploying the device, the screw 9 is manipulated to lower the jack so that the vehicle may be rolled above the same until the axles of the vehicle are superposed in alined relation to the saddle 26. The winch bar 16 is then operatively engaged with the screw 9 to manipulate the same until the spider frame is elevated to lift the vehicle off the floor or foundation 12. It will now be seen that the body 20 resting on the balls 19, the spider frame and vehicle supported thereby may be readily rotated around the center of the screw 9, facilitating the operation of cleaning or painting which may be in progress.

Claims:

1. A jack as characterized, comprising a spider frame; a jack screw; and a table mounted on said jack screw and rotatively supporting said frame.
2. A jack as characterized, comprising a spider frame; a jack screw; a table mounted on said screw for supporting said frame; and rolling devices disposed between said table and said frame to carry said frame.
3. A jack as characterized, comprising a spider frame; a jack screw; a table mounted on said screw, having an annular groove; and a series of balls disposed in said groove to carry said frame.
4. A jack as characterized, comprising a

jack screw; a table mounted on said screw; a spider body rotatively mounted on said table; and a plurality of arms adjustably mounted on said body to accommodate vehicles of various sizes.

5. A jack as characterized, comprising a jack screw; a table mounted on said screw; a spider body having divergent open-ended socket bores; and a plurality of arms slidably mounted in said socket bores.

6. A jack as characterized, comprising a jack screw; a table mounted on said screw; a spider body having divergent open-ended socket bores; a plurality of arms slidably mounted in said socket bores; and a plurality of rolling devices disposed between said table and said body to rotatively support said body.

7. A jack as characterized, comprising a jack screw; a table mounted on said screw; a spider body having divergent open-ended socket bores; and a plurality of arms removably mounted in said socket bores.

In testimony whereof I have signed my name to this specification in the presence of two subscribing witnesses.

ISAAC WATTS FURMAN.
